COMBINED PENCIL SHARPENER AND
ENVELOPE OPENER

Preble D. K. Hatch, Bangor, Maine

Application November 22, 1940, Serial No. 366,617

5 Claims. (Cl. 120—1)

This invention relates to a combined pencil sharpener and letter opener.

It is an object of the invention to provide a pencil sharpener which may be readily carried in the pocket, having a knife blade operably mounted for severing the edge of an envelope whereby the envelope is opened.

A further object of the invention resides in providing a device of the above-mentioned character which is simple and durable in construction, reliable and efficient in operation, and inexpensive to manufacture.

Other objects and advantages of the invention will be apparent during the course of the following description.

In the accompanying drawing forming a part of this specification and in which like numerals are employed to designate like parts throughout the same;

Fig. 1 is a perspective view of the device,
Fig. 2 is an elevation of one end of the device,
Fig. 3 is an elevation of the opposite end of the device,

Fig. 4 is a cross sectional view of the device,
Fig. 5 is a perspective view showing the device in position for severing the edge of an envelope, and

Fig. 6 is a fragmentary enlarged view of the knife blade in its normal position showing the inclined slot in the side of the groove below the point of the knife blade.

In the drawing, wherein for the purpose of illustration I have shown a preferred embodiment of my invention, the numeral 5 denotes an elongated body of rectangular shape preferably constructed of a suitable light material. The body is provided with a conical bore 6 eccentrically disposed to the longitudinal axis of the body which extends from one end of the body to a point adjacent the opposite end. One side of the body is provided with a longitudinal groove 7 to receive a knife blade 8 pivotally mounted at one end by a pivot screw 9. The groove 7 intersects the bore 6 and the cutting edge 10 of the knife blade is normally disposed in the side of the bore so as to engage a pencil inserted in the bore whereby the pencil is sharpened upon rotation of the pencil or the body. The free end of the knife blade has a vertical extension 11 disposed in the recessed portion 12 of the body, the upper end of the extension being bent at right angles to extend across the top of the body providing a finger piece 13. A coil spring 14 is disposed between the finger piece 13 and top of the body having one end seated in a re-

cess 15 in the top and its opposite end engaged with the projection 16 pressed from the finger piece. The spring 14 normally holds the knife blade in operative position for use as a sharpener, but upon depressing the finger piece 13 the knife blade swings downwardly into operative position for severing the edge of an envelope when the edge is inserted between the cutting edge of the blade and side of the groove 7 as shown in Fig. 5. When the edge of the envelope is inserted between the cutting edge and side of the groove, the knife blade is depressed and the device is drawn along the edge of the envelope which causes the cutting edge to sever the edge of the envelope. The side of the groove 7 towards which the cutting edge of the blade moves is provided with a downwardly inclined slot 17 at the end directly beneath the outer end of the cutting edge 10 of the knife blade so that when the blade is depressed the point will enter the slot and not be injured by contact with the body.

In use, the device serves as a pencil sharpener when the knife blade is disposed in its normal position. When employed as an envelope opener, the edge of the envelope is inserted in the groove beneath the cutting edge of the knife blade and upon depressing the knife blade and drawing the device along the edge of the envelope the edge is severed and the envelope opened.

It is to be understood that the form of my invention herein shown and described is to be taken as a preferred example of the same and that certain changes in the shape, size, and arrangement of the parts may be made without departing from the spirit of the invention or the scope of the subjoined claims.

Having thus described my invention, I claim:

1. A device of the character described comprising a body having a longitudinal rectangular groove in one side and a conical bore extending longitudinally of the body in communication with the bottom of the groove, and a knife blade pivotally mounted in the bottom of said groove for swinging movement towards one side of the groove.

2. A device of the character described comprising a body having a longitudinal rectangular groove in one side and a conical bore extending longitudinally of the body in communication with the bottom of the groove, a knife blade pivotally mounted in the bottom of said groove towards one side of said groove, and means for depressing said knife blade.

3. A device of the character described com-

prising a body having a longitudinal groove in one side and a conical bore extending longitudinally of the body in communication with said bore, a knife blade pivotally mounted at one end in said groove having its cutting edge projecting into the bore, and an extension projecting upwardly from the free end of said blade for depressing the blade to move the cutting edge towards one side of the groove.

4. A device of the character described comprising a body having a longitudinal groove in one side and a conical bore extending longitudinally of the body in communication with said bore, a knife blade pivotally mounted at one end in said groove having its cutting edge projecting into the bore, an extension projecting from the free end of said blade having its end bent at right angles to extend over the top of said body to provide a finger piece for depressing said knife blade, and a spring beneath said finger piece

normally holding said knife blade in a raised position.

5. A device of the character described comprising a body having a longitudinal groove in one side and a conical bore extending longitudinally of the body in communication with said groove, a knife blade pivotally mounted at one end in said groove having a cutting edge projecting into said bore, an extension projecting upwardly from the free end of said blade having its end bent at right angles to extend over the top of said body to form a finger piece for depressing the blade to move the cutting edge towards one side of the groove, the side of the groove towards which said blade is moved being provided with an inclined slot to receive the point of the cutting edge, and a spring disposed beneath said finger piece adapted to normally hold said blade in a raised position.
